MOTION SIGN OR THE LIKE

Edward A. Stroman, Chicago, Ill., assignor of forty-nine per cent to Peter A. Cavallo, Peter A. Cavallo, Jr., Elsie Schifferle Cavallo, and M. Agatha Cavallo

Application May 24, 1935, Serial No. 23,311

13 Claims. (Cl. 40—52)

This invention relates to a motion sign or the like.

An object of the invention is to provide a motion sign which may be caused to operate continuously or discontinuously, control means being provided for varying the operation of the sign when operated discontinuously. A further object is to provide a motion sign equipped with compact operating mechanism adapted to be housed within a very narrow space, the sign being of such simple and light construction as to be useful for window displays, advertising racks on vehicles, etc. A further object is to provide brush-propelled mechanism whereby the sign is operated intermittently, the intervals of pause being controlled by a second brush-operated member. Other specific objects and advantages will appear as the specification proceeds.

The invention is illustrated, in its preferred embodiment, by the accompanying drawings, in which—

Figure 1 is a front view in elevation of a motion sign embodying my invention; Fig. 2, a rear view in elevation; Fig. 3, a rear view, with the operating mechanism all removed with the exception of the sign disk; Fig. 4, a broken sectional view, the section being taken as indicated at line 4 of Fig. 2; Fig. 5, a broken detail sectional view, the section being taken as indicated at line 5 of Fig. 4; and Fig. 6, a rear view in elevation of a modified form of control disk.

In the illustration given, A designates the side frame; B, the movable sign member; C, operating mechanism for rotating the sign; and D, control mechanism.

The frame A may be of any suitable construction. In the illustration given, it comprises a front board 10 and a rear board 11 spaced apart by filler board 12. Each of the boards is preferably formed of cardboard, but may be of any other suitable material. As shown more clearly in Figs. 3 and 4, the filler board 12 is cut away at 13 to provide a circular recess and the rear board 11 is cut away at 14 to provide a small recess or slot aligned with recess 13.

The front board 10, as shown more clearly in Fig. 1, is provided with an aperture 15 through which sign representations on the moving sign member B become visible.

The sign member B may be of any suitable shape, type or construction. In the illustration given, it consists of a circular disk bearing on its outer face various types of representations which are adapted to be brought into registration with the aperture 15 when the disk B is rotated. In

the illustration given, the representations consist of numerals 16. On its rear face, the disk B is provided near its periphery with an interrupted band 17 which may be formed of buckram or any other suitable mesh cloth or the like. The band 17 is interrupted by recesses 18 extending inwardly from the edge of the sheet B. Spaced inwardly of recesses 18 and aligned therewith are patches 19 of buckram or other suitable material. Each recess 18 and its aligned area 19 fall within the same sector when formed by imaginary lines drawn from the central axis of the disk.

A tubular member 20 has a front flange 20^a engaging the outer face of board 10 and is also equipped with a tubular neck 21 which extends through aligned recesses in the board 10 and sign member B and rear wall 11. The front board 10, sign disk B, rear board 11, and control disk D are separated by washers 22. The tubular neck 21 is interiorly threaded to receive the threaded locking pin 23.

The operating mechanism D may be of any suitable type or construction. In the illustration given, I provide a crank arm 24 which has its upper extremity turned to form a ring 25 through which the shank of pin 23 extends. The crank arm 24 extends from the point of connection with ring 25 toward one side of the board 11 in a substantially horizontal plane and is then bent at right angles to form a vertical shank 26. The lower end of shank 26 is looped about the movable arm 27 of the vibrator element 28. In view of the well known construction of the solenoid-operated vibrator element 28, a detailed description will not be given. In order to movably confine the crank arm 24 in close relation to the board 11, I loop an elastic rubber band 29 about the crank 24 at its bend and then secure the band to the rear board 11 by means of adhesive tape 30.

Secured to the horizontal portion of crank 24 near its bend is a brush element 31. The element 31, as illustrated, comprises a cardboard support 32 which is grooved to receive the crank arm 24 and held in rotatable position upon the crank 24 by tape 33. To the lower portion of board 32 are secured by glue or other suitable means a plurality of brushes 34, each brush being formed of a series of bristles which are stitched together near their base. The brushes are preferably rigidly secured by glue or other suitable means in the position shown more clearly in Fig. 5. The forward ends of the brushes 34 extend through the opening 14 in the rear board member 11 and engage the buck-

ram band 17 on the rear surface of disk B. The brush ends in the position illustrated ratchet over the mesh cloth member 17 when the crank arm 24 is moved downwardly, but engage the cloth to rotate the disk B when the arm 24 is moved upwardly.

The control disk D may be of any suitable construction. As illustrated, the disk D is provided adjacent one edge with a recess 35 which is 10 adapted to be brought into alignment with a small aperture 36 in the rear board 11. When the recess 35 and small aperture 36 are together, the separated cloth areas 19 are accessible from the rear of the control disk D and 15 permit a second brush element 37 carried by the crank arm 34 to engage one of the areas 19. To the rear side of the control disk D and spaced to the inside of the recess 35 is a circular mesh cloth backing 38 which may be secured by adhesive to the disk D. The brush 37 is 20 so mounted as to enable part of the bristles to continuously engage the mesh backing 38 and also the cloth mesh area 19 when the latter becomes exposed through the alignment of recess 25 35 with aperture 36. The brush 37 is the same in construction as brush 31.

In Fig. 6, is illustrated a modified form of control disk D' provided with two recesses 35a.

In the operation of the device, the vibrator 28 30 is set into operation by closing a suitable switch (not shown) and the crank arm 24 is moved upwardly and downwardly in rapid succession, the confining elastic member 29 serving to hold the crank closely adjacent the rear board 11. The brush member 31 ratchets over the buckram strip 17 as the crank arm swings downwardly but engages the strip as the crank moves upwardly and moves the strip forwardly, thus bringing about 35 a rotation of disk B. When, however, the brushes 40 reach one of the recesses 18, as shown more clearly in Fig. 5, the ends of the brush bristles reciprocate through the recess without effecting any movement of disk B. The brush 31 is 45 thus rendered ineffective for producing further movement of disk B until the control mechanism D advances the disk B sufficiently to bring another portion of the strip 17 into contact with the brush.

The brush 37 being constantly in engagement 50 with the fabric backing 38 of control disk D, causes control disk D to rotate continuously. When the disk D has rotated to the point that recess 35 thereof becomes aligned with aperture 36 of the rear board 12, the bristles of brush 37 extend through the recess 35 and aperture 36 and engage one of the areas 19, thus operating to advance the disk B a short distance, but yet sufficiently to bring the next segment of fabric strip 17 into engagement with the bristles of brush 31. The brush 31 then 55 continues to rotate the disk B until the next recess 18 is brought into register with brush 31.

With the construction described, the various 60 representations 16 on disk B are brought into registration with aperture 15 and there caused to pause for a predetermined period of time. After the pause, the disk B is again rotated to bring the next representation into view from the front of the sign. With the control disk illustrated 65 in Fig. 2, the period of pause is substantially the same with respect to each of the representations; however, when the modified form of disk D' illustrated in Fig. 6 is used, the period of pause will vary as to the representations. It 70 will be understood that the periods can be varied 75

widely through changes in the form of the control disk.

The motion sign is of simple and compact construction. The parts thereof are light and require very slight energy for operation. The entire sign may be flexed slightly without interfering with the operation of the parts, thus enabling the sign to be fitted into the curved sign racks on vehicles and in display windows. 5

It will be understood that instead of employing a vibrator of the type illustrated, any other suitable motor or actuating element may be employed, for example, actuating mechanism, as illustrated in my co-pending application Serial No. 710,186, for Motion sign or the like, filed February 15 7, 1934 may be employed, such actuating mechanism being responsive to movements in a vehicle. Instead of the vibrator, an ordinary small electric motor or the like may be used. 10

While in the foregoing illustration, I have 20 shown certain specific mechanisms and arrangements of parts, it will be understood that wide departure from the specific forms illustrated may be made without departing from the spirit of my invention. 25

The foregoing detailed description has been given for clearness of understanding only, and no unnecessary limitations should be understood therefrom, but the appended claims should be construed as broadly as permissible, in view of the 30 prior art.

I claim:

1. An exhibition device comprising: a frame, a sign member movably mounted thereon, means for moving said sign within discontinuously, and 35 control means for initiating the movement of said sign during the intervals in which said first-mentioned means does not move said sign, said control means being effective also to maintain said sign in motion until it is moved by said first- 40 mentioned means.

2. An exhibition device comprising: a frame, a sign member carried by said frame for movement thereon, means for moving said sign member discontinuously, a control member, means for 45 moving said control member continuously, and means cooperating with said control member and sign member for initiating movement of said sign at a predetermined period after its movement by said first-mentioned means is discontinued, said 50 control means being effective also to maintain said sign in motion until it is moved by said first-mentioned means.

3. An exhibition device comprising: a frame, a sign member rotatably mounted thereon, a fabric 55 strip applied to one face of said sign member, brush means engaging said fabric strip, and means for moving said brush to effect rotation of said sign member, said means including a crank arm pivotally carried by said frame, and 60 electrically operated means for reciprocating said crank.

4. An exhibition device comprising: a frame, a sign member movably supported thereby, said sign being provided with an interrupted band of 65 fabric, a brush movably supported in contact with said band, means for actuating said brush to move said sign while said brush is in engagement with said band, and means for again bringing said brush into engagement with said band 70 after the engagement of said brush with said band has been interrupted.

5. An exhibition device comprising: a frame, a sign member rotatably mounted thereon, a fabric strip secured to said sign member but having 75

spaced interruptions therein, a brush mounted for movement and adapted to engage said strip to effect movement of said member, means for moving said brush to bring the same into engagement with said strip until said strip is interrupted, and means after said brush is no longer in engagement with said strip for again bringing said strip into engagement with said brush.

5 6. An exhibition device comprising: a frame, a sign member rotatably carried thereby, means for rotating said sign member discontinuously, a control member rotatably mounted upon said frame, and means associated with said control member for starting the rotation of said main sign member after its rotation has been interrupted for a predetermined interval.

10 7. In a device of the character set forth, a frame provided with an aperture, a sign member rotatably mounted thereon and adapted upon rotation to bring representations successively into registration with said aperture, a discontinuous fabric strip secured to the rear side of said sign member, a plurality of spaced fabric areas secured also to the rear side of said sign member, brush means adapted to engage said fabric strips, and a control member preventing the engagement of brush means with said spaced fabric areas except when the brush means is not in engagement with the first-mentioned fabric strip.

15 8. In apparatus of the character set forth, a frame member, a sign member rotatably carried thereby, a broken fabric band secured to one side of said sign member, spaced fabric areas radially aligned with the spaces between said first-mentioned broken band, brush means for engaging said fabric band and said fabric areas, and continuously operated control means adapted to maintain said brush means out of contact with said fabric areas except during the interval when the brush means is not contacting said first-mentioned band.

20 9. In apparatus of the character set forth, a frame, a sign member rotatably mounted thereon, a control member also rotatably mounted on said sign member, a broken fabric band secured to said sign member, a plurality of spaced fabric patches secured also to said sign member, a fabric body secured to said control member, and brush means adapted to engage said fabric band, patches, and fabric body, said control member serving to maintain said brush means out of contact with said fabric patches except at predetermined intervals, and means for actuating said brushes.

25 10. In apparatus of the character set forth, a frame having an aperture therein, a sign member bearing representations on one side adapted to be brought into registration with said aperture, a fabric band secured to the outer portion of the back of said sign member, said band being broken

30 at intervals by spaces, fabric patches secured to the back of said sign member and in alignment with said spaces, a control member rotatably carried by said frame, a fabric strip applied to said control member, a sheet between said control member and said sign member, said sheet being provided with an aperture aligned with said broken band and a second aperture aligned with said patches, said control member being also provided with an aperture adapted to be brought in line with said last-mentioned aperture, brushes having bristle ends adapted to extend through the apertures in said sheet and said control member to engage said broken band and said fabric patches, and means for reciprocating said 15 brushes.

35 11. In apparatus of the character set forth, a frame comprising spaced walls, one of said walls being provided with an aperture and the other of said walls being provided with a pair of spaced apertures, a sign member rotatably mounted in said frame and bearing on one side representations adapted to be brought into registration with said first-mentioned aperture, said member being also provided on its rear side with spaced fabric bands, at least one of which is broken by spaces, a control member rotatably mounted adjacent the rear wall of said frame and being provided with an aperture adapted to be aligned with one of said pairs of apertures, said control member being provided with a fabric disk, brushes supported so as to have their ends extending through the apertures of said rear wall and said control member when the latter is aligned with one of said pairs of apertures, and means for reciprocating said brushes to bring the ends thereof into contact with said fabric bands.

40 12. In apparatus of the character set forth, a frame, a pair of movably mounted members thereon, one of said members bearing representations adapted to be exposed to view successively, said members being provided on one side with roughened areas, brushes mounted so as to bring their ends into engagement with said roughened surfaces, means for reciprocating said brushes to move said members, and cooperating means associated with said movably mounted members for moving discontinuously said member-bearing representations thereon.

45 13. An exhibition device comprising: a flexible frame, a flexible sign member movably mounted thereon and bearing representations, said sign member being provided on one side with a roughened surface, a tiltable brush member mounted for reciprocal movement so that its ends are brought in contact with said roughened surface, and electrically operated means carried by said frame for reciprocating said brush means.

50 EDWARD A. STORMAN. 60
